UNITED STATES PATENT OFFICE.

CARL W. WEISS, OF BROOKLYN, NEW YORK.

REVERSING DEVICE FOR OIL-ENGINES.

1,228,857.

Specification of Letters Patent.

Patented June 5, 1917.

Application filed June 1, 1916. Serial No. 101,132.

To all whom it may concern:

Be it known that I, CARL W. WEISS, a citizen of the United States, and residing in the borough of Brooklyn of the city of New York, county of Kings, in the State of New York, have invented certain new and useful Improvements in Reversing Devices for Oil-Engines, of which the following is a specification, reference being had to the accompanying drawings, forming a part hereof.

This invention relates generally to reversible oil engines and is concerned particularly with the provision of improved reversing devices therefor. It has been proposed heretofore to start and reverse oil engines by means of compressed air admitted to the cylinder or cylinders but the apparatus provided has been entirely independent of the fuel distributor so that there has always been present the danger of admitting the compressed air at a time when its pressure would be added to the compression pressure within the cylinder and thereby create a pressure above that for which the cylinder was designed. Again, such controlling apparatus for starting and reversing has often been associated with means for by-passing the fuel but this arrangement is objectionable for the reason that the speed gradations, such as are ordinarily obtained by manipulation of the throttle, cannot be secured by a simple by-pass valve. In cutting off the fuel suddenly from the cylinder in this manner, not only are strains imposed upon the engine but the compressed air for reversing is apt to be thrown into the cylinder before the speed has dropped, with uniform retardation, to a point where reversal can be effected without undue shocks. The disadvantages of the structures noted briefly are overcome by the present invention by associating the reversing devices operatively with the throttling devices so that the two can never be placed in such relative conditions that injury to the motor or unsatisfactory operation can ensue. In the accompanying drawings very simple means for realizing the improvements have been illustrated but it will be evident as the description proceeds that some other operative connection between the throttle and reversing lever may be devised and serve the same function as the safety locking lever illustrated herein. The broad objects of the invention having been pointed

out, it remains to describe the illustrative embodiment shown in the drawings, in which,—

Figure 1 is a view in perspective of a four-cylinder oil engine to which the invention is applied.

Fig. 2 is a fragmentary detail view, in plan, and on a somewhat larger scale showing the relative disposition of the throttle and reversing lever and the interposed safety locking lever.

Fig. 3 is a fragmentary detail view, in elevation, of the devices shown in Fig. 2.

In the interest of clearness, there has been illustrated in the drawings, a four-cylinder oil engine α to which the invention is applied but it is to be understood that the improved devices are applicable generally to internal combustion engines of any type. At one end of the crank case α' of the engine α there are supported, as through suitable brackets α^2 and α^3 , an oil distributor b and an air distributor c the construction of which is immaterial so far as this invention is concerned. The controlling valves in these distributors may carry on their stems b' and c' spiral gears b^2 and c^2 adapted to mesh with a common gear d carried on the crank-shaft d' or operatively engaged therewith. The fuel oil may be supposed to pass to the oil distributor b from a suitable source of supply e through a pipe e' and be led from the distributor to the respective cylinders α^4 through distributing pipes b^3 , all in substantially the manner well known. The oil supply may be controlled at the distributor b by means of a suitable throttle lever f with which is carried a segment f' for a purpose which will appear later.

In much the same manner as described with respect to the controlling and distribution of the oil to the several cylinders, there is provided a source of compressed air, indicated at g , from which the air is led to the distributor c through a pipe g' and this air finally passes to one of the cylinders α^4 through the appropriate distributing pipe c^3 and in proper time relation to the cycle of operations within the cylinders. The flow of air to the distributing valve in the casing c is controlled by what may be termed a reversing lever h , although it will be understood that by manipulation of this lever the air is permitted to pass to the cylinders α^4 for starting the engine or for reversing it.

This lever h is carried on the stem h' of the controlling valve for the air (not illustrated) in such relation thereto that when the lever is in its median position, as shown 5 in the drawings, the air is cut off from the distributing pipes c^3 and the lever h lies substantially parallel to the throttle lever f , the median position of which serves to place the oil distributing pipes b^3 in communication 10 with the oil supply.

So far as described, there is no particular relation between the oil distributor b and the air distributor c except that the controlling valves therein are operated in unison from 15 the crank-shaft d' . But even this harmonious operation would not prevent the attendant from so manipulating the throttle lever f and the reversing lever h as to throw compressed air, say at about the usual pressure 20 of 150 to 175 pounds, into one of the cylinders at the time when the piston was about to commence its compression stroke. If the pressure of the air were thus added to the compression pressure the engine would be 25 subjected to an internal pressure far above that for which it is designed and the danger of a serious accident would be great. Again, if compressed air were admitted into the cylinders without regard to the cycle of operations 30 going on therein or the speed of the engine the results would be equally disastrous were the air opposed to the operating force. It is the principal object of this invention to provide positive safety locking 35 devices which shall be so related to the fuel controlling devices and the air controlling devices as to prevent their being placed in such relative conditions as to permit injurious or unsatisfactory operation of the engine 40 under any circumstances. As noted before, the specific character of these improved safety devices may be altered through wide ranges and the invention of the illustrated embodiment retained. However, 45 there is shown in the accompanying drawings a simple locking lever which is operatively interposed between the reversing lever h and the throttle lever f and so associated therewith that neither of these 50 controlling levers can be so manipulated as to bring about dangerous or unsatisfactory operation of the engine. The locking lever i , as shown, is pivotally mounted adjacent its mid-section on a pivot-pin i' carried on a 55 bracket a^5 fixed to the crank case a' between the brackets a^2 and a^3 for the distributors b and c , respectively. One end of the locking lever i has a beveled nose i^2 which cooperates with the segment f' of the throttle 60 lever f while the other end of the lever has a similar nose i^3 for coöperation with a reversely beveled boss h^2 formed on the under face of the reversing lever h .

In operation, with the throttle lever f in 65 its cut-off position, the starting lever h can

be moved from its median position to the "ahead" position thereby admitting compressed air into the proper cylinder for starting the engine ahead. After the engine has been turned over in this manner the 70 throttle will be manipulated to admit the fuel into the cylinders and when it is thus manipulated the edge of the segment f' will engage the beveled face of the nose i^2 on the locking lever i so as to cause this nose 75 to ride up on the circular portion of the segment and thereby rock the lever to a position where the other nose i^3 will lie in the path of the beveled boss h^2 . When the starting lever h is then moved to its median 80 position to cut off the air, it will be evident that it will be held against movement to reversing position by the engagement of the boss with the nose i^3 . Of course, during operation of the engine with the boss 85 in the position described the attendant may move the starting lever h to the "ahead" position but such movement will serve only to admit compressed air to the cylinders in such relation to the moving pistons as to 90 have no effect thereon and be exhausted at each exhaust stroke. If now, it be assumed that the engine is to be reversed, the segment f' must be carried out of engagement with the nose i^2 of the locking lever i in 95 order that this lever may rock sufficiently to permit the nose i^3 to be carried out of the path of the boss h^2 . To effect this release of the locking lever i , the throttle lever f must be turned to a position where the fuel is 100 cut off. During this movement, the fuel will be gradually throttled until, when the segment has moved out of engagement with the nose i^2 , the engine will have been slowed down by a uniform retardation, to a point 105 where the air can be safely admitted to effect the reversal without injury or undue shock. After the curved portion of the segment f' has been moved out of engagement with the nose i^2 , the reversing lever h may 110 be thrown to the "back" position during which movement the beveled nose i^3 will ride idly over the beveled edge of the boss h^2 . Movement of the lever h to either the "ahead" position or the "back" position may 115 be limited conveniently by means of lugs h on the upper face of the distributor c . The reversal just described evidently cannot be brought about except when the fuel is cut off from the cylinders since the locking lever engages the boss h^2 , nor can this reversal be effected until after the engine has 120 been slowed down in the usual manner by movement of the throttle valve to its cut-off position. After the air has been admitted to effect the reversal in the manner described, fuel may then be admitted into the cylinders for operation of the engine by moving the throttle valve again to its median 125 position. After the air has been admitted to effect the reversal in the manner described, fuel may then be admitted into the cylinders for operation of the engine by moving the throttle valve again to its median 130 position. In returning to its median

position the segment f' will engage the beveled nose i^2 and throw the safety lever to its locking position and with the nose i^3 again in the path of the boss h^2 but on the 5 other side thereof, so that the reversing lever h cannot be moved past the nose i^3 to the "ahead" position. And so, after each manipulation of the levers f and h , the locking lever is automatically released from or 10 fixed in safety position, according to the positions of said levers, thereby insuring against the creation of conditions within the cylinder in which dangerous or unsatisfactory operation might ensue. The controlling lever h for the air may always be 15 moved to admit air in proper phase relation to the cycle of operations but it can never be moved to a position in which the compressed air will be opposed to the compressive or explosive force within the cylinders.

As indicated hereinbefore, it will be obvious to the skilled mechanic that other devices for operatively connecting or locking 25 the levers f and h , or their equivalents, can be substituted for the simple safety lever i , without loss of any of the advantages herein described, but all such modified constructions are to be deemed within the spirit of 30 this invention provided the stated objects are realized and the modifications fall within the scope of the appended claims.

I claim as my invention:

1. In an internal combustion engine, in 35 combination with a source of fuel, an independent source of compressed starting medium, means to control the fuel, independent means to control the compressed medium for starting and reversing, and devices operatively interposed between said 40 means for locking one of said means against movement to a certain predetermined position relative to the other of said means when the other of said means is in predetermined position.

2. In an internal combustion engine, in 50 combination with a source of fuel, an independent source of compressed starting medium, a throttle lever, an independent starting and reversing lever for the compressed medium, and means operatively interposed between said levers for locking one 55 of said levers against movement to a certain predetermined position relative to the other of said levers when the other is in predetermined position.

3. In an internal combustion engine in 60 combination with a source of fuel, an independent source of compressed starting medium, means to control the fuel, independent means to control the compressed medium for starting and reversing, and de-

vices operatively interposed between said means to lock the controlling means for the compressed medium against movement to a 65 position in which the compressed medium would be admitted to oppose the fuel while the fuel is being admitted.

4. In an internal combustion engine, means to control the fuel, means to control the 70 compressed medium for starting and reversing, and devices operatively interposed between said means to lock the controlling means for the compressed medium against movement to one actuating position while 75 the fuel is being admitted, while permitting free movement thereof to the other position.

5. In an internal combustion engine in combination with a source of fuel, an independent source of compressed starting 80 medium, means to control the fuel, means to control the compressed medium for starting and reversing, and a locking lever interposed between said means and operative 85 to hold said means against movement to certain predetermined relative positions.

6. In an internal combustion engine in combination with a source of fuel, an independent source of compressed starting 90 medium, a throttle lever, an independent lever to control the compressed medium for starting and reversing, and a locking lever interposed between said levers and operative to hold them against movement to certain 95 predetermined relative positions.

7. In an internal combustion engine in combination with a source of fuel, an independent source of compressed starting medium, a throttle lever, a segment thereon, 100 an independent lever to control the compressed medium for starting and reversing, a reversely beveled boss on the starting lever, and a locking lever interposed between said first named levers and having its ends 105 disposed to coöperate with said segment and boss, respectively, to maintain the throttle lever and starting lever in predetermined relative positions.

8. In an internal combustion engine in 110 combination with a source of fuel, an independent source of compressed starting medium, a fuel distributer, a compressed air distributer, a single gear to drive said distributers in unison, a throttle lever, an 115 independent starting and reversing lever, and a locking lever operatively interposed between said first named levers to prevent the simultaneous admission of fuel and air under objectionable conditions.

This specification signed this 26th day of May, A. D. 1916.

CARL W. WEISS.
